TOY TRUCK

Clayton E. Steinke, Salem, Oreg.

Application October 6, 1949, Serial No. 5,322

Term of patent 14 years

(Cl. D34—15)

To all whom it may concern:

Be it known that I, Clayton E. Steinke, a citizen of the United States, residing at Salem, in the county of Marion and State of Oregon, have invented a new, original, and ornamental Design for Toy Trucks, of which the following is a specification, reference being had to the accompanying drawing, forming part thereof.

I claim:

The ornamental design for a toy truck, as shown.

CLAYTON E. STEINKE.
